UNITED STATES PATENT OFFICE.

JOEL FRANK BARNETT, OF ALVA, KENTUCKY.

RAIL SPLICE AND CLAMP.

Application filed May 7, 1925. Serial No. 28,647.

To all whom it may concern:

Be it known that I, JOEL F. BARNETT, a citizen of the United States, residing at Alva, in the county of Harlan and State of Kentucky, have invented certain new and useful Improvements in Rail Splices and Clamps; and I do hereby declare the following to be a full, clear, and exact description of the invention, such as will enable others skilled in the art to which it appertains to make and use the same.

The invention relates to means for joining the meeting ends of railroad rails and has for its object the provision of improved means for forming the splice and clamping the ends of the rails together, the device being of a character that dispenses with the use of nuts and bolts in making the joint.

A further object of the invention is the provision of means by which the rails may be quickly and securely joined and one in which the means for making the joint may be quickly removed when it is desired to replace a rail or for any other purpose.

To this end the invention consists of two members hingedly secured together and adapted to engage the meeting ends of the rails, the hinge member having a slidable pintle carrying a feather that engages a spline in the hinge knuckles of the two members that will lock the two members in engagement with the rails, one of said members having studs to engage bolt openings in the rails and the other member provided with sockets to receive the extremities of the studs.

The construction and operation and advantages of the invention will be described in detail hereinafter and will be found illustrated in the accompanying drawings, in which

Figure 1 is a side view of meeting ends of two rails with the improved rail splice and clamp in position,

Figure 2 a bottom plan view of the rail splice and clamp,

Figures 3 and 4 are sectional views on the planes indicated by the lines 3-3 and 4-4, respectively, of Figure 1,

Figure 5 a horizontal longitudinal sectional view,

Figure 6 a longitudinal sectional view of the hinge member,

Figure 7 a view in perspective of one of the members, and

Figure 8 a similar view of the other member.

In the drawings similar reference characters will be used to designate corresponding parts throughout the several views.

The improved rail splice and clamp comprises two members designated generally A and B, respectively, said members being hingedly connected together by means of hinge knuckles 1 on member A and hinge knuckle 2 on member B. Member A has a base plate 3 that seats under the base of the rails C and C' and a splice bar 4 adapted to engage one side of the webs of said rails and integrally connected with the outer edge of base plate 3 by means of an inclined web 5. The member B has a splice bar 6 that engages on the opposite side of the rails from the splice bar 4 and an inclined supporting member 7 carrying the knuckle 2 heretofore described.

Splice bar 4 is provided with a plurality of studs 8 that are adapted to engage the usual bolt openings in railroad rails C and C', and splice bar 6 is provided with sockets 9 aligned with the studs 8 and adapted to receive their extremities when in engagement with the rail joint.

The pintle of the hinge, designated 10 is provided with a feather 11 that slidably engages a spline 12 in one of the end knuckles 1 and the adjacent knuckle 2, and it will be understood that when the feather is in engagement with both of the splines the two members will be locked in engaging position with the rails. The pintle 10 is extended beyond the hinge knuckle as shown at 13 and has mounted thereon an expandable coil spring 14 with its extremities engaging a washer 15 and a suitable nut or other member 16 engaging the outer end of the pintle. It will be understood that with this construction when the device is in the position shown in the drawings the two members A and B will be securely locked together and by means of the studs 8 engaging the bolt openings in the ends of the rails, the meeting ends of the rails will be held joined.

When it is desired to release the device from the rails, the pintle 6 will be moved to compress the coil spring 14 so as to remove the

- feather 11 from the spline 12 in knuckle 2 and the two members may then be swung apart and removed from the rails, and when placed on the rails, the members being in open position, the device will automatically lock through the instrumentality of the spring 14 when the two members are properly positioned and the splines 12 in knuckles 1 and 2 are alined.
10. What is claimed is:
1. In a rail splice and clamp, two members adapted to engage the meeting ends of railroad rails, a hinge including a pintle pivotally connecting the members, and means cooperative with the pintle of the hinge to lock the members in engagement with the rails.
  2. In a rail splice and clamp, two members adapted to engage the meeting ends of railroad rails, said members being provided with alined hinge knuckles, a pintle engaging said knuckles, a feather on said pintle, and the knuckles formed with a spline to engage said feather.
  3. In a rail splice and clamp, two members adapted to engage the meeting ends of railroad rails, said members being provided with alined hinge knuckles, a pintle slidably engaging said knuckles, a feather on said pintle, the knuckles formed with splines to engage said feather, and resilient

means to hold the pintle in position to engage the feather with the splines in two of the knuckles.

4. A rail splice and clamp comprising 35 complementary members hingedly secured together and adapted to engage the meeting ends of railroad rails, studs on one of said members adapted to engage openings in the rails, the other member provided with 40 sockets to receive the ends of said studs, and means to lock said members in engagement with the rails.

5. A rail splice and clamp comprising 45 complementary members hingedly secured together and adapted to engage the meeting ends of railroad rails, studs on one of said members adapted to engage openings in the rails, the other member provided with 50 sockets to receive the ends of said studs, said members being hinged together by means of alined hinge knuckles and a pintle slidably engaging said knuckles, two adjacent knuckles being splined, a feather on the pintle engaging said splines, the end of the 55 pintle remote from the feather extended beyond the knuckles, and an expansible coil spring carried by said extended end of the pintle and normally urging the feather into engagement with splines.

In testimony whereof I affix my signature.

JOEL FRANK BARNETT.
